(57) **CLAIM**

We claim the ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a first embodiment of a display screen or portion thereof with graphical user interface, showing our new design; and,

FIG. 2 is a front view of a second embodiment of a display screen or portion thereof with graphical user interface, showing our new design.

The outer perimeter broken lines in the drawings represent a display screen or portion thereof and forms no part of the claimed design. The remaining broken lines in the drawings depict portions of the graphical user interface which form no part of the claimed design.

1 Claim, 2 Drawing Sheets
